FIG. 5

UNITED STATES PATENT OFFICE

MATTHEW SCHMALZGRUBER, OF MAPLEWOOD, MISSOURI

FOLDING FURNITURE

Application filed November 19, 1930. Serial No. 496,588.

This invention relates generally to folding furniture, and more specifically to a structure adapted for use in homes and apartments where the conservation of space is important and which provides for the folding of several articles of furniture into a single housing, the predominant object of the invention being to provide a structure of this type which includes one or more beds, a table, and a plurality of chairs, all of which when not in use may be folded into a common, compact housing.

Fig. 1 is a horizontal section of my improved structure showing the beds thereof in the extended positions as when in use.

Fig. 2 is a view similar to Fig. 1 but showing the beds folded into the housing and the table and chairs of the structure arranged in the extended positions they occupy when in use.

Fig. 3 is a vertical section through the structure showing all of the elements of furniture folded into the housing of the structure.

Fig. 4 is a vertical section of the structure showing the table and the chairs in their extended positions.

Fig. 5 is a view similar to Fig. 4 but showing the beds extended.

Fig. 6 is a fragmentary section showing a portion of one of the doors of the structure and a foldable chair fixed thereto.

In the drawings, wherein is shown for the purpose of illustration, merely, one embodiment of the invention, A designates the housing of my improved structure, said housing including rear, end, bottom, and top walls secured together in the usual manner and suitably decorated to provide an attractive structure. Preferably, though not necessarily, the housing is surmounted by an upper structure B, which provides a plurality of compartments, said compartments being adapted to receive such articles as dishes, glassware, silver, etc., or, if desired, one of the compartments may house a radio receiving set.

Arranged within the housing A and secured to the rear wall thereof is a guiding member 1 (Figs. 3, 4, and 5). This guiding

member extends longitudinally of the rear wall of the housing A and is spaced vertically with respect to the bottom wall of the housing. The guiding member 1 is provided with a guideway or channel 2 which extends longitudinally of the guiding member from end to end thereof. Secured to the bottom wall of the housing A is a strip of material 3 and a wider strip of material 4, said strips being spaced apart from each other slightly to provide a guideway or channel 5 which is defined by the inner edges of the strips 3 and 4 and a portion of the top face of the bottom wall of the housing A. The guideway or channel 5 is in vertical alinement with respect to the guideway or channel 2 in the guiding member 1.

Supported for sliding movement longitudinally of the housing A is a panel 6 which constitutes a part of a bed carrier C, said bed carrier including a pair of vertically spaced elements 7 and 8 which are secured to the panel 6 and extend outwardly therefrom. The element 8 is slightly larger than its associated element 7, as shown clearly in Fig. 5, and interposed between said elements at their inner end portions is a spacing and bracing member 9. The elements 7 and 8 and the intermediate member 9 are securely fixed together by a fastening element 10, which passes through all of said elements, as shown in Fig. 5. From the foregoing it is plain that the bed carrier C provided by the combination of the elements 6, 7, 8, and 9 is movable as a unit longitudinally of the housing A and within said housing, such movement of the bed carriage C being guided by the guideways or channels 2 and 5 into which the upper and lower edge portions of the panel 6 are extended. To facilitate free movement of the panel 6 with respect to the guideway 5, I provide said panel with rollers 11 which are arranged in cutout portions formed in the panel. These rollers are rotatably mounted on suitable axes 12 supported by the element 8 and they contact with the portion of the top face of the bottom wall of the housing A which constitutes the base of the guideway or channel 5.

Adjacent to their outer ends the elements 7

95

100

and 8 are provided with elongated slots 13 and 14, said slots being extended longitudinally of said elements, as shown most clearly in Fig. 1. The slots 13 and 14 receive the 5 opposite end portions of an elongated, vertically disposed bolt 15 which provides a pivot for a bed rail 16, said bed rail having an enlarged head portion 17 (Fig. 1) at its rear end, and the bolt 15 being extended through 10 the slots 13 and 14 in the elements 7 and 8 and through an aperture formed in said enlarged head portion of the bed rail. Because of this arrangement, it is plain that the bed rail 16 is pivotally supported by the bed carrier C, the outer end portion of said bed rail being capable of swinging in an arc of a circle about the pivot 15. Also, because the pivot 15 is extended through the elongated slots 13 and 14, it is plain that the bed rail is 15 capable of movement longitudinally of the elements 7 and 8. The bed rail, at its outer end, is provided with an enlarged portion 18 (Figs. 1 and 5) which is rigidly fixed to said bed rail and constitutes a unitary part thereof.

20 **Hingedly attached to the bed rail 16 by means of hinges 19 are beds 20 and 21.** The beds are arranged side by side with the bed rail interposed between them, as shown in Fig. 1, and because of the hinged arrangement of the beds with respect to the bed rail said beds may be moved upwardly and arranged parallel with respect to each other, so that the transverse dimensions of the beds are extended perpendicularly. Each of the 25 beds includes a box-like frame provided by end elements 22, an outer side member 23, and a bottom member 24. At the inner side of the frame of each bed no wall element is provided, as the bed rail 16 serves as the inner side wall elements of both beds when said beds are in their lowered and extended position, as shown in Fig. 1. Within the frame of each bed I provide the usual bed spring and mattress, but these elements are not shown in the drawings.

Secured to each bed at a point adjacent to the outer end thereof is a leg structure 25. This leg structure is hingedly attached to the bottom of the associated bed by means of a 30 hinge 26 and is foldable rearwardly and upwardly against the bottom of the bed. As already stated, the beds 20 and 21 are movable to elevated positions where their transverse dimensions are arranged perpendicularly, in which positions the transverse dimensions of said beds are arranged parallel with each other. To maintain the beds in such perpendicular positions I provide a pair of elements 27 which are pivoted at 28 to the 35 enlarged head portions 17 of the bed rail 16. When the beds are in their lowered position, as shown in Figs. 1 and 5, the elements 27 are in the position best illustrated in Fig. 1. When, however, the beds are elevated as already explained, and it is desired to main-

tain the beds in such elevated positions, the elements are swung about on their pivots until they assume the positions in which they are illustrated in dotted lines in Fig. 1. This will cause the outer portions of the elements 27 to be positioned beneath the extensions 22' at the inner ends of the end elements 22 of the frames of the beds, whereby the beds will be maintained in their elevated position.

As shown clearly in Fig. 5, the housing A 40 is provided with a strip of material 29, said strip of material being fixed within the housing and being extended longitudinally thereof. The strip of material 29 is provided with depressions in which small antifriction rollers 30 are rotatably arranged. Also, the element 18 at the outer end of the bed rail 16 is provided with cavities in which antifriction rollers 31 are rotatably arranged, said rollers 31 being extended a slight distance below the bottom face of said element 18.

When the beds 20 and 21 of my improved structure are in their lowered and extended positions, as shown in Figs. 1 and 5, and it is desired to fold said beds and move same into the housing A, the outer sides of the beds are grasped and moved upwardly and inwardly in an arc of a circle about the pivotal points of the hinges 19. This will result in the transverse dimensions of the beds being arranged in vertical parallelism, as shown clearly in Figs. 3 and 4. The elements 27 are then moved to the positions where they will maintain the beds in their elevated positions. Pressure is then applied to the bed 45 structure, which will cause the bed carrier C to move in the direction indicated by the feathered arrow in Fig. 1, and during such movement of the bed carrier the outer end portions of the beds are swung in the direction indicated by the unfeathered arrow in Fig. 1 about the pivot 15. This movement of the beds and the bed carrier C will be continued until the outer ends of the beds pass into the housing A at the right-hand end of 50 the opening in the front wall of the housing, which is closed by the doors 32 of the housing, and when the beds have passed into the housing said beds will be disposed as shown in Figs. 3 and 4.

The purpose of the antifriction rollers 30 and 31 is to facilitate movement of the folded beds as just described, the beds moving along the rollers 30 as such movement of the beds takes place and the rollers 31 moving along a transverse member 33 located within the housing when the outer end portions are moved into said housing. When the beds have been moved into the housing A as described, and as best shown in Fig. 2, a pair of elements 34, which are pivoted at 35 to the front wall of the housing, are moved to positions where the ends of said elements opposite to the pivoted ends thereof are moved into engagement with the outermost of the beds, whereby said 55

folded beds are held rigid with respect to the housing A.

Fixed to the bottom wall of the bed 20 at the inner edge thereof is a guiding member 36, and arranged at the opposite or outer edge of said bottom wall of said bed is a similar guiding member 37. The guiding members 36 and 37 extend longitudinally of the bed 20 and are provided with guideways 38 and 39, respectively, the guideways of the elements 36 and 37 being alined with each other in a direction parallel with respect to the bottom wall of the bed. 40 designates a table carrier which comprises a panel, said panel having its upper and lower edge portions inserted into the guideways of the guiding members 36 and 37, whereby said panel is capable of moving longitudinally with respect to the bed 20.

Secured to the panel 40 at the outer face thereof is a vertically disposed member 41 (Fig. 2) to which a wing of a hinge 42 is attached, the associated wing of said hinge being secured to a block 43. The block 43 is secured to the inner end portion of a table-supporting rail 44 which is preferably provided with portions 45 of increased thickness. 46 designates a table top which is hingedly attached to the table-supporting rail 44 by means of hinges 47, said hinges being attached to said table top and to said table-supporting rail at the thickened portions 45 thereof. At the outer end portion of the table top 46 and at the bottom face thereof I attach, by means of hinges 48, a leg structure 49 which serves to support the table top when same is in its extended position, as shown in Fig. 4, the lower end of the leg structure contacting with the floor.

When it is desired to use the table of my improved structure, said table is positioned as illustrated in Figs. 2 and 4, the inner end of the table being supported, through the instrumentality of the hinge 42, by the panel 40, and the outer end portion of the table will be supported by the leg structure 49. When the table is to be moved to its folded position, pressure is applied thereto and the table carrier, which is the panel 40, is moved in the direction indicated by the feathered arrow in Fig. 2. At the same time the table top is moved on the hinges 47 to a position where it is arranged on edge, and the leg structure 49 is folded against the table top. 55 The table top 46 and table-supporting rail 44 are then swung on the hinge 42 in the direction indicated by the unfeathered arrow in Fig. 2 until the table top is arranged flat against the bottom wall of the bed 20, whereupon the elements 50, which are pivoted at 51 to the bottom wall of the bed 20, will be moved to a position where the table structure is engaged by said elements 50 to maintain said folded table structure in its folded position with respect to the bed 20.

The doors 32 of the structure preferably comprise pairs of door sections at opposite sides of the door opening of the housing A; that is to say, at each side of the door opening a door is hinged at 52 to the front wall of the housing A, which door comprises a pair of door sections hinged together at 53. Fixed to each door section of the doors 32 is a pair of spaced apart extensions 54 which are provided with alined, vertically extended slots 55. 56 designates a chair seat (Fig. 6) which is secured to the associated door section by a horizontal rod 57, said rod passing through the chair seat at the rear portion thereof and having its opposite end portion extended through the slots 55 in the extensions 54.

The chair seat, adjacent to its forward edge and at its bottom face, is provided with an element 58 to which a pair of spaced legs 59 is pivotally attached at 60. These legs 59 when in their operative positions extend downwardly and rearwardly from the pivotal point 60, and at their approximate longitudinal centers said legs 59 have attached to them by means of a pivot 61 a leg structure 62. The leg structure 62 is interposed between the spaced legs 59 of the chair, and when said leg structure is in its operative position as illustrated in Fig. 6, the upper end of the leg structure 62 contacts with a block 63 secured to the bottom face of the chair seat. The back of the chair is provided by an element 64 which is of approximately the same width as the chair seat, said element being secured at its upper end to the associated door section and having a laterally extended lower end portion 65, the inner end of which contacts with the door section to give the seat back the proper inclination. The back 64 preferably will be formed from some suitable yieldable material, which will give some resiliency to the seat back, and said seat back will be covered by suitable cloth or leather covering material which will enhance the appearance thereof. Secured to the block 63 is a hook 66, and attached to the associated door section at the point where the seat back is attached thereto is a strip of suitable yieldable material 67, said strip of yieldable material having an eye 68 attached thereto at its free end.

When my improved structure is being used with the table in an extended position, the doors 32 may be moved to positions where they extend outwardly at substantial right angles with respect to the front wall of the housing A. The chairs being arranged in their unfolded condition, said chairs will be in the proper positions to be occupied by persons seated at the table. When it is desired to fold the table and move same into the housing A, the chairs will be folded against the associated door sections, as shown in Figs. 1 and 3, and the strips 64 will be arranged about the outside of said folded chairs with

the eyes 68 engaging the hooks 66. This will cause the chairs to be held in their folded conditions against the door sections. When the chairs are folded as described, the chair backs will extend across the tops of the folded chairs and will extend downwardly in front of said folded chairs, each of said chair backs being capable of hinging at the point designated by the reference character 69 in Fig. 3 to permit such arrangement of the chair backs.

With the chairs folded as described, and with the beds and table folded within the housing A, it is plain that the doors 32 may be moved to positions where they close the door opening at the front of the housing. When this is done it is obvious that all of the foldable furniture elements will be folded into the housing A. Also, when the beds are being used the doors 32 and chairs may be disposed as shown in Fig. 1, or, if preferred, one or both of the doors may be extended outwardly so as to permit use of one or more of the chairs.

25 It is seen, in view of the foregoing description, that a unitary article is produced which provides for the convenient use and ready disposition, when not in use, of a number of articles of furniture, and because of its construction my improved structure provides a very attractive article of furniture. While I illustrate my improved structure as being apart from the building in which it is used, it is obvious that if desired the housing A 30 of my structure may be built into a wall of a building.

In order to support the beds of my improved structure when they are being folded or unfolded while in outwardly extended positions, I provide a leg 75 which is hinged at 76 to the outer end portion of the bed rail 16. The leg 75 is provided with a roller 77 which is rotatably mounted at the lower end of said leg so that said roller contacts 40 with the floor, whereby said leg and roller aid in swinging the beds about when they are being moved to position for introduction into the housing of the structure. The leg is movable to the inoperative position in which same is shown by dotted lines in Fig. 5 when the beds are moved into the housing of the structure, and a catch 78 (Fig. 2) is provided for maintaining said leg in such inoperative position.

55 I claim:

1. A structure of the class described comprising a housing, a carrier mounted within said housing, means for guiding said carrier for sliding movement with respect to said housing, a bed-supporting rail pivotally and slidably attached to said carrier, and a pair of beds hingedly attached to said bed-supporting rail.

2. A structure of the class described comprising a housing, a carrier mounted within

said housing, means for guiding said carrier for sliding movement with respect to said housing, a bed-supporting rail pivotally and slidably attached to said carrier, a pair of beds hingedly attached to said bed-supporting rail, said beds being foldable together in upright positions, and means for maintaining the beds in such upright positions.

3. A structure of the class described comprising a housing, a carrier mounted within said housing, means for guiding said carrier for sliding movement with respect to said housing, a bed-supporting rail pivotally and slidably attached to said carrier, a pair of beds hingedly attached to said bed-supporting rail, said beds being foldable together with the transverse dimensions thereof extended perpendicularly and being movable into said housing, means for maintaining said beds in such perpendicular positions, and means for maintaining the positions of the folded beds within the housing.

4. A structure of the class described comprising a housing, a carrier mounted within said housing, means for guiding said carrier for sliding movement with respect to said housing, a bed-supporting rail pivotally and slidably attached to said carrier, a pair of beds hingedly attached to said bed-supporting rail, and foldable legs attached to the beds at the outer ends thereof.

5. A structure of the class described comprising a housing, a bed carrier mounted within said housing, means for guiding said bed carrier for sliding movement with respect to said housing, a bed pivotally supported by said carrier and foldable within said housing, a table, and means for foldably attaching said table to said bed, the last-mentioned means including a table carrier, guiding elements fixed to said bed for supporting said table carrier for sliding movement, a table-supporting rail, means for pivotally attaching said table-supporting rail to said table carrier, and hinge means for hingedly attaching said table to said table-supporting rail.

6. A structure of the class described comprising a housing, a bed carrier mounted within said housing, means for guiding said bed carrier for sliding movement with respect to said housing, a bed pivotally supported by said carrier and foldable within said housing, a table, means for foldably attaching said table to said bed, the last-mentioned means including a table carrier, guiding elements fixed to said bed for supporting said table carrier for sliding movement, a table-supporting rail, means for pivotally attaching said table-supporting rail to said table carrier, and hinge means for hingedly attaching said table to said table-supporting rail, and a foldable leg structure for supporting the outer end of said table.

7. A structure of the class described comprising a housing, a bed carrier mounted

within said housing, means for guiding said bed carrier for sliding movement with respect to said housing, a bed pivotally supported by said carrier and foldable within
5 said housing, a table, means for foldably attaching said table to said bed, the last-mentioned means including a table carrier, guiding elements fixed to said bed for supporting said table carrier for sliding movement, a
10 table-supporting rail, means for pivotally attaching said table-supporting rail to said table carrier, and hinge means for hingedly attaching said table to said table-supporting rail, a foldable leg structure for supporting
15 the outer end of said table, said table being foldable into position adjacent to said bed, and means for maintaining said table in such folded position.

8. A structure of the class described comprising a housing, a carrier mounted within said housing, means for guiding said carrier for sliding movement with respect to said housing, a bed-supporting rail pivotally attached to said carrier and movable to a position where its longitudinal dimension is parallel with respect to the direction of travel of said carrier, and a bed hinged along one of its longitudinal sides to said rail so as to be foldable upwardly and movable with said
20 rail into said housing.

9. A structure of the class described comprising a housing, a carrier mounted within said housing, means for guiding said carrier for sliding movement with respect to said housing, a bed-supporting rail pivotally attached to said carrier and movable to a position where its longitudinal dimension is parallel with respect to the direction of travel of said carrier, and a pair of beds hinged along
25 longitudinal sides thereof to said rail so as to be foldable upwardly and movable with said rail into said housing.

In testimony that I claim the foregoing I
hereunto affix my signature.

45 MATTHEW SCHMALZGRUBER.
